UNITED STATES PATENT OFFICE.

FRANCIS MADDISON LONG AND ERNEST SCHATTNER, OF NORWICH,
ENGLAND.

PREPAYMENT ELECTRIC METER.

SPECIFICATION forming part of Letters Patent No. 618,699, dated January 31, 1899.

Application filed July 18, 1898. Serial No. 686,248. (No model.)

To all whom it may concern:

Be it known that we, FRANCIS MADDISON LONG and ERNEST SCHATTNER, subjects of the Queen of Great Britain, residing at Norwich, in the county of Norfolk, England, have invented a certain new and useful Improvement in Prepayment Electric Meters, of which the following is a specification.

Our invention relates to a certain improvement in prepayment electric meters or electric meters of the class controlled by the insertion of a coin or coins which places certain parts of the apparatus in position to allow a current to pass through the same for a given period of time only.

In carrying out our invention we utilize the principle that a current going through a voltameter deposits on one plate of same from the other a quantity of metal exactly proportionate to the strength of the current by causing one plate to be carried by a balanced arm which is overbalanced by the weight of the coin or coins, so as to make an electrical contact, whereby a current will pass through the voltameter until a certain amount has been deposited from or on the plate carried by the arm onto or from a fixed plate, with the result that the plate so carried is lightened or made heavier and the arm rises, thus breaking the circuit, or the voltameter is otherwise effected, according to its nature, the arm in any case being operated thereby.

One form of apparatus constructed according to our invention is illustrated in the accompanying drawing, which is an elevation showing the main or principal features of such an apparatus.

On a suitable back or base *a* and properly insulated is an arm or lever *b*, supported by a suitable knife-edge or the like situated slightly below the center of gravity of the lever, so that the lever is in unstable equilibrium and remains overbalanced either on one side or the other. The knife-edge or the like is carried on the block *c*, and directly above and attached to the lever is a rod *d*, having a weight at the end which assists in overbalancing the lever. At one end the lever carries a screw *e*, provided with a nut or weight *f*, by which the balance of the lever may be adjusted, and also a rod *g*, preferably

suspended to it on a knife-edge and carrying weights *h*. A stop *i*, secured to the base, serves to check the downward movement of the arm. On the other side of the block *c* is a receptacle *j* for the coins, preferably suspended on a knife-edge in the lever, as shown, and farther along the arm and on the same side of the pivoting-point as the receptacle *j* is suspended a rod *k*, adapted to carry weights *l*, representing a certain number of coins. This rod is also preferably hung on a knife-edge. At the extreme end is hung the positive electrode *m* of the voltameter *n*, such electrode being also preferably carried by a knife-edge in some suitable way. The negative electrode *o* is fixed in some suitable way. As shown, it is attached to the base *a* at point *p*. The electrodes may be of copper, in which case the solution will be also a copper one. The lever also carries at or about the same end a contact-maker of some suitable form. As shown, it consists of a U-shaped or bifurcated strip *q*, suitably insulated from the lever, the ends of such strip dipping into mercury-cups *r* *s*, the former of which is a terminal of the main wire *t* and the latter a terminal of wires *u* and *u'*, the first of which leads through resistance *v* to the main terminal *w* and the latter leads to the fixed plate *o* of the voltameter through point *p*, and a connection is provided from the suspended plate *m* through the lever *b* to the block *c* and thence by the wire *u'* and resistance *v'* also to the main terminal *w*.

The operation is as follows: The lever is to start with just overbalanced and the contact-maker *q* is out of the mercury of the cups *r* *s* and the circuit is broken. Upon a coin or coins being dropped into the receptacle *j* the lever is overbalanced at that side and the contact-maker is placed in the mercury of the cups, as shown in the drawing. The current entering at terminal *u'* divides, part passing through resistance *v'*, wire *u'*, block *c*, lever *b*, positive electrode *m* to negative electrode *o*, out by terminal *p*, wire *u'*, to mercury-cup *s*, contact-maker *q*, cup *r*, and out, and part going through resistance *v* and wire *u* and joining the other circuit at cup *s*. Copper from electrode *m* is thus deposited on *o* proportionately to the current being used, and as soon as electrode *m* is sufficiently lightened

the lever *b* will rise and be again overbalanced and the contact-maker *q* be removed from the mercury, so that the circuit is broken until another coin or coins is inserted in the receptacle.

5 The rod *k* is adapted to carry disks or weights equal to a certain number of coins, one or more of which weights can be placed thereon by the collector to balance the coins taken from the receptacle.

10 It will be understood that the particular arrangement of the apparatus may be varied without departing from our invention. For instance, instead of restoring or putting the 15 parts in working position by placing a coin in a receptacle which directly overbalances the lever the coin may be caused to move a weight or allow a weight to be moved along the lever, the lever being graduated if necessary, or to vary the weight on the lever or the like.

15 It should also be understood that with the apparatus herein described there may be used a suitable counting and registering device 20 which will indicate the number of coins inserted, as well as suitable means for preventing the withdrawal of coins or the insertion of improper articles, if deemed necessary, all of such arrangements being of a well-known 25 character.

30 What we claim is—

1. In a prepayment electric meter and in combination, a lever, a circuit, a contact-making device in the same operated by the lever, 35 means controlled by a coin for moving the lever and making the contact, a voltameter, the passage of the current through which will raise the lever and break the contact, and means connecting the voltameter and the lever, substantially as described.

2. In a prepayment electric meter and in combination, a pivoted weighted lever, a circuit, a contact-making device in the same operated by the lever, means controlled by a coin for moving the lever and making the contact, a voltameter, and an electrode of the same carried by the lever and which electrode the passage of the current will alter the weight of, and so allow the lever to be raised and break the circuit substantially as described. 45

3. In a prepayment electric meter and in combination, a balanced lever, a voltameter, an electrode of same carried by said lever, a circuit, a contact-maker in the same carried 55 by the lever, a receptacle for coins on the lever, and a compensating device also on the lever to balance the coins removed, substantially as described.

4. In a prepayment electric meter and in combination, a pivoted lever, means for controlling the balance of same on one side of the pivot-point, a coin-receptacle on the other side, a compensating device for the coins removed, on the same side as the coin-receptacle, a voltameter, an electrode of same suspended to the lever, the weight of which is altered by the passage of the current so that the balance of the lever is disturbed and an insulated contact-maker carried by the lever, 65 substantially as described. 70

In testimony whereof we have hereunto set our hands in the presence of two subscribing witnesses.

FRANCIS MADDISON LONG.
ERNEST SCHATTNER.
